[57] CLAIM

The ornamental design for a roof rack support for a passenger car, as shown and described.

DESCRIPTION

FIG. 1 is a front perspective view of a roof rack support for a passenger car, shown at an enlarged scale with the roof rack being shown in broken lines according to our novel design; and,

FIG. 2 is a rear perspective view of a roof rack support for a passenger car, with the roof rack, the opposite roof rack support and a portion of the car being shown in broken lines according to our novel design.

The broken lines are for illustrative purposes only and do not form any part of the claimed design. Those portions of the roof rack support not shown in FIGS. 1 and 2 form no part of the claimed design.
